UNITED STATES PATENT OFFICE

FRED E. LEUZINGER, OF DETROIT, MICHIGAN

WALL CONSTRUCTION

Application filed April 12, 1929. Serial No. 354,526.

The present invention relates to improvements in wall construction and has for its principal object to provide a hollow wall which includes blocks or slabs of predetermined shapes that are arranged in such a manner as to preclude the admission of cold air or moisture through the wall and at the same time provide for a continuous air space or horizontally communicating vertical air spaces between the inner and outer wall members or sections.

Another important object of the invention is to provide a wall construction wherein the pre-cast wall blocks or slabs are adapted to be arranged so as to form molds for reinforced concrete pillars or columns thus obviating the necessity of having to employ wooden forms.

A further and important object of the invention is to provide a wall construction wherein certain of the blocks or slabs may be employed as a base to support horizontally disposed concrete reinforced beams that are employed to support cross sills or rafters.

A further object is to provide a wall construction of the above-mentioned character which is simple, inexpensive strong and durable.

Other objects and advantages of the invention will become apparent from the following description when taken in connection with the accompanying drawings.

In the accompanying drawings wherein like reference characters indicate corresponding parts throughout the same;

Figure 1 is a perspective view showing two courses of adjacent walls wherein my improved building blocks or slabs are employed, to form the vertical flues and showing the corner flue being partially filled with concrete having reinforcing rods extending transversely therethrough.

Figure 2 is a plan view of the uppermost course of blocks shown in Figure 1.

Figure 3 is a similar view of the lowermost course illustrated in Figure 1.

Figure 4 is a view similar to Figure 1 showing the adjacent walls built higher up and more clearly disclosing the manner in which the flat blocks are employed to form a base

for the horizontally disposed concrete beams.

Figure 5 is a top plan view looking down on Figure 4 to disclose the manner in which the rafters extend across the concrete horizontally disposed beams.

Figure 6 is a detail perspective view of one of the rectangular shaped blocks or slabs.

Figure 7 is a similar view of one of the T-shaped units forming a salient portion of the present invention.

Figure 8 is a detail perspective view of one of the angular corner blocks.

Figure 9 is a plan view of a portion of a hollow wall wherein modified blocks are used.

Figure 10 is a detail perspective view of the T-shaped unit that is employed in forming the modified wall structure shown in Figure 9.

Figure 11 is a view similar to Figure 9 illustrating a further modification of the blocks.

Figure 12 is a detail perspective view similar to Figure 10 of the substantially T-shaped unit used in conjunction with the wall structure shown in Figure 11; and

Figures 13 and 14 show still further forms of blocks which may be used in lieu of the blocks of Figures 6 and 7 to form a wall in accordance with this invention.

In the drawings wherein for the purpose of illustration is shown the preferred embodiment of my invention, the numeral 1 designates a substantially rectangular shaped block or slab that may be formed of any suitable composition. The numeral 2 designates an angular unit consisting of a substantially T-shaped block that is employed in constructing the hollow wall, while 3 designates the right angular corner block. In constructing the hollow wall, a series of blocks 1 are arranged in spaced relation and the same are positioned on their lower longitudinal edges to form the outer member of the wall and interposed between the spaced blocks of this outer wall member are the head portions 4 of the T-shaped blocks 2. The inner wall member has its rectangular shaped block 1 arranged in staggered relation with respect to the blocks 1 of the outer wall member and the blocks of the inner wall member are spaced

with respect to each other to receive the head 4 of the T-shaped units 2 and in this manner, the leg portions 5 of the T-shaped units located in the outer wall member will be spaced from the inner faces of the intermediate portions of the respective rectangular shaped blocks 1 in the inner wall member as at 2^a.

In a similar manner, the leg portions of the T-shaped units arranged in the inner wall member will be spaced from the inner face of the opposed blocks 1 of the outer wall member, whereby to form a continuous air space or horizontally communicating vertical air spaces 5^a. Furthermore, the joints in the inner wall member will be out of alignment with the joints in the outer wall member so that cold air or moisture cannot penetrate through the entire wall structure, as will be appreciated by those skilled in the art.

The second course of blocks that are arranged on top of the lower course are arranged in reverse order. That is to say the blocks 1 in the outer wall member of the second course will not be in vertical alignment with the blocks 1 of the lower course nor will the head portions 4 of the T-shaped units 2 be disposed in vertical alignment with the head portions of the lower course so that the blocks in the alternate courses of the wall that is undergoing construction will only be in alignment as is obvious from the construction shown in Figure 4.

In constructing the corner of the building, it is necessary to employ the angular blocks shown in Figure 3 and these blocks are only used in alternate courses, the slabs or blocks 1 of the adjacent walls forming the corner portions of every other course.

The arrangement of the blocks in the manner as shown and described provides a mold for the concrete reinforcing pillars or columns 6 that may be reinforced through the medium of the vertically extending reinforcing rods 7. This will obviate the necessity of having to employ the conventional wooden forms as is now required in building concrete structures having vertical pillars or columns.

Furthermore I utilize the rectangular shaped blocks or slabs 1 to provide a base for supporting the horizontally disposed concrete beams 8 that may also be reinforced by the rods 9 extending longitudinally therethrough. In Figure 4, I clearly illustrate the manner in which the concrete slabs or blocks 1 are employed to provide the base for the concrete beams and it will be observed that the blocks 1 are arranged horizontally to rest on the upper edges of the subjacent course of blocks and T-shaped units and these horizontally disposed blocks that support the concrete beams are indicated at 10.

The horizontal beams 8 provide means for supporting the cross sills or rafters shown at 11 in Figure 5. The end of the rafters or cross

sills have interfitting relation with respect to the blocks of the inner wall member as clearly shown in Figures 4 and 5 and after the rafters or cross sills have been placed in position, additional blocks are placed above the course of blocks that rests on the concrete beams 8 until the wall has been built up to the desired height.

In Figure 9 of the drawings, I have illustrated a slight modification of the blocks wherein the ends of the rectangular shaped blocks 12 are formed with dove-tailed notches 13 to receive the beveled end portions 14 formed at the free ends of the arms of the head portion of the T-shaped units 15 one of which is shown in Figure 10.

In Figure 11, there is shown a further modification of the hollow wall wherein the T-shaped blocks or units 16 have the heads thereof merging with the leg portion through the medium of the tapered sides 17 and the free end portion of the leg of each T-shaped unit shown in Figure 11 has its sides beveled as indicated at 18.

Otherwise the blocks are arranged in the same relation with respect to each other as the blocks shown in Figures 2 and 3.

It will thus be seen from the foregoing description, that I have provided a hollow wall construction that will be strong and durable and at the same time afford the proper installation properties. Also by arranging the blocks in the manner as shown and described, the use of wooden forms to provide molds for the vertical reinforcing concrete pillars or columns is eliminated.

While I have shown the preferred embodiment of my invention, it is to be understood that minor changes in the size, shape and arrangement of parts may be resorted to without departing from the spirit of the invention or the scope of the appended claims.

Obviously, the U-shaped unit or block 19 of Figure 13 may be used with the rectangular block 20 of Figure 14 in the manner taught in Figures 2 and 3 and in lieu of the blocks 1 and 2, to form a similar wall. In a like manner, the angular blocks or units may take any one of many other forms without departing from the spirit of the invention.

What I claim is:

1. In a wall construction of the class described, inner and outer spaced wall sections, each including courses of blocks, each course comprising spaced rectangular shaped blocks having angularly shaped grooves therein and T-shaped units interposed between the spaced blocks having angular projections for being received within the grooves, the outer faces of the heads of the T-shaped units lying flush with the outer faces of the rectangular blocks, the leg portions of the T-shaped units being spaced from the inner faces of the opposed rectangular shaped blocks, the rectangular shaped blocks in the inner wall section being

disposed in staggered relation with respect to the rectangular shaped blocks in the same course of the outer wall section.

2. In a wall construction of the class described, inner and outer spaced wall sections, each including courses of blocks, each course comprising spaced rectangular shaped blocks having angularly shaped grooves therein and T-shaped units interposed between the spaced blocks having angular projections for being received within the grooves, the outer faces of the heads of the T-shaped units lying flush with the outer faces of the rectangular blocks, the leg portions of the T-shaped units being spaced from the inner faces of the opposed rectangular shaped blocks, the rectangular shaped blocks in the inner wall section being disposed in staggered relation with respect to the rectangular shaped blocks in the same course of the outer wall section, the blocks in one course being disposed in staggered relation with respect to the blocks in the next adjacent course.

In testimony whereof I affix my signature.
FRED E. LEUZINGER.
